RECOVERY OF UNSAPONIFIABLES FROM CONCENTRATES CONTAINING THE SAME

Arthur Ira Gebhart, Union, N. J., assignor to Colgate-Palmolive-Peet Company, Jersey City, N. J., a corporation of Delaware

No Drawing. Application May 4, 1949,
Serial No. 91,421

8 Claims. (Cl. 260—397.2)

1

The present invention relates to the recovery of an unsaponifiable fraction, and more particularly the selective recovery of sterols, from an unsaponifiables concentrate containing fatty material admixed therewith.

Heretofore, various means have been proposed for the separation of an unsaponifiable concentrate, and more particularly a highly concentrated sterol fraction. A common technique has been the use of molecular distillation on the natural fats and oils, and the recovery of an unsaponifiable fraction such as the sterols from the overhead. Such procedure is limited since the sterols for example occur in the triglyceride in minute quantities (e. g. cholesterol occurs in animal oils and fats to the extent of about 0.1 to 1%), impure sterol mixtures are obtained and only in fair yield, and complex operating techniques including short path high vacuum distillation are required.

In processes involving extraction with a solvent for the unsaponifiables (e. g. alcohol or ethylene dichloride), serious difficulty is encountered in the presence of a fatty material. The fatty material (e. g. soap) may absorb, dissolve, or cause emulsification with the solvent to a degree such that phase separation of the solvent extract containing the unsaponifiables is difficult, and extraction is incomplete. Distillation techniques are not fully suitable to recover particular fractions from the solvent extract. Similarly, crystallization of unsaponifiables, and more particularly sterols, from the solvent extract is not economically practical on a commercial scale, as appreciable loss is encountered and impure products are recovered due to cocrystallization, due to the tendency of the unsaponifiables to remain in the fatty material instead of crystallizing out because of their low concentration, and due to concurrent precipitation of other types of matter.

Broadly, the present invention comprises the recovery of an unsaponifiable fraction, more particularly a highly concentrated sterol fraction, from a concentrate of the same containing fatty material in admixture therewith by extraction with particular solvents for the sterols and other unsaponifiables. Moreover, selected sterols present in the solvent extract may be recovered therefrom, utilizing the solubility characteristics of the solvent in conjunction with the formation and recovery of an insoluble sterol-oxalic acid complex. Accordingly, the solvent extract may be reacted with oxalic acid to form a separable oxalate complex with cholesterol and similar types of sterols. These selected sterols may be recovered as pure compounds upon separation and decomposition of the complex.

As solvents, suitable liquid organic esters may be employed which dissolve the unsaponifiables

5

including the sterolic material and are relatively poor solvents for saponified fatty material. It is preferred to use the lower esters containing not more than about eight carbon atoms in the molecule, with at least two carbon atoms in the acid radical moiety of the ester. More particularly the lower aliphatic esters, or the lower fatty acid esters, having the above type structure may be selected for extraction purposes. For the recovery of selected sterols from the solvent extract by formation of an oxalate complex, it is desired to use generally such ester solvents which do not possess a free alcoholic or keto group, e. g. lower fatty acid esters of lower monohydric alcohols. Accordingly, such solvents as methyl acetate, n-propyl acetate, isopropyl acetate, n-butyl acetate and its isomers, amyl acetate, methyl amyl acetate, methyl propionate, amyl propionate, ethyl butyrate, ethyl propionate, etc. may be used, but it is preferred to use ethyl acetate generally.

10

The mass suitable for extraction with ethyl acetate or similar solvent is an unsaponifiable concentrate, more specifically a sterol concentrate, having saponified fatty material admixed therein. These concentrates in addition to sterols may contain a number of other substances such as tocopherols, vitamins, oils, phosphatides, pigments, etc. Such concentrates of unsaponifiables or sterols may be derived generally either from the splitting (e. g. hydrolysis, saponification, etc.) of a fat, fatty oil, or fatty wax of animal, vegetable, or marine origin and the subsequent removal of a portion of the split fatty material, or by the separation of at least a fraction of the fatty material without decomposition, e. g. solvent fractionation, to obtain thereby the desired unsaponifiable or sterol concentrate in each instance. More specifically, these concentrates may be derived from such fatty materials as tallow, lard, wool fat, halibut liver oil, tall oil, wheat germ, cottonseed, soybean, rapeseed and cocoa butter. In general, cholesterol may be recovered from the sterol concentrates derived from fatty materials of animal origin, and particular phytosterols such as stigmasterol may be obtained from concentrates emanating from vegetable materials by practice of the various features of the present invention.

15

Accordingly, the present invention contemplates the use of concentrates resulting from hydrolysis of the natural fats, fatty oils, and the like in any suitable manner, and the removal of the major portion of the fatty acids and/or glycerine therefrom. The still bottoms resulting from the distillation of the products of continuous counter-current high pressure fat-splitting operations are preferred, such as the processes illustrated by Ittner, U. S. Patents Nos. 2,435,745 and 2,458,170. More particularly it is desired to

20

2

use the second bottoms obtained by recycling the original still bottoms through the splitting zone. There is thus recovered an enriched bottoms fraction which usually contains over 5% sterols by weight. A sterol concentration of at least about 5% is efficacious since the losses during processing are thereby of a relatively small order.

After the practice of such hydrolytic procedures followed by distillation, a concentrated phase containing fatty acids, sterols, some glycerine, and minor amounts of other constituents will remain in the still. The major portion of fatty acids and glycerine may be or may have been distilled at either atmospheric or reduced pressure in any suitable manner, leaving a dark colored residue containing significant amounts of fatty acids and in which the unsaponifiables and particularly the sterols have been concentrated.

Similarly, the reaction products obtained by alcoholysis of a fatty material, as indicated by Allen et al., U. S. Patent No. 2,383,579; Dreger, U. S. Patent No. 2,383,596 and Trent, U. S. Patents Nos. 2,383,632 and 2,432,181, may be utilized to obtain the sterol concentrate. The alcoholysis reaction products may be flash distilled directly from the alcoholysis zone to separate unreacted alcohols, esters, and glycerine, whereby a concentrated residue is obtained containing the sterols and other unsaponifiables as valuable by-products. Alternatively, the reaction mixture containing chiefly the esters, fatty acids, and glycerine, may be subjected to phase separation whereby there are recovered separate ester and glycerine layers. The fatty acid esters and/or glycerine in each layer, may be removed in any suitable manner such as by either batch or continuous distillation. The residues after separation of these and other volatile constituents may be admixed, if desired and consist of a relatively small volume of material containing generally unreacted fatty acid glycerides as well as the sterols in a high concentration and unimpaired condition.

Likewise, the sterols may be found concentrated in the extracts or raffinates from the solvent treatment of fatty materials. The efficacy of liquid-liquid extraction as a means of fractionating fatty mixtures is favorable for the selective separation or concentration of the unsaponifiable or sterol content in a particular phase. Particularly suitable for the recovery of a concentrate are the counter-current fractionation processes for fatty materials using a one- or two-solvent system. The solvents may be strongly or weakly polar, or non-polar in character. The solvents which appear most suitable are furfural, the hydrocarbons such as hexane, and the liquified normally gaseous ones including propane, butane, etc. With solvents such as propane, appropriate adjustments of temperature and/or pressure are necessary in order to recover the desired concentrate. Any solvent in the layer containing the sterols may be removed in any suitable manner.

The still residues and other sterol concentrates containing non-sterolic material, e. g. fatty acids and/or their esters, may be saponified in any manner, either by batch, semi-continuous or continuous operations. The saponification may be accomplished by means of a suitable basic saponifying agent, such as those having an alkali metal as the cation, e. g. sodium hydroxide, potassium hydroxide, or sodium carbonate. These alkali metal bases are highly desired be-

cause no interference due to water-insoluble soaps is encountered in subsequent solvent extraction of aqueous material; and it has been found that soaps derived from such bases function equally well in solvent extraction of dried soap material. The proportion of alkaline saponifying agent is variable, depending upon the extent of saponification desired. Generally, at least a molar equivalent (and preferably an excess) of saponifying agent is utilized in order to insure complete saponification of the free acids and the fatty acids in combined form, such as in the form of esters of the sterols and other esters, present in the still residues. It is preferred to convert the bottoms to soap by the usual type of kettle boil method, wherein the saponifiable material is boiled with strong aqueous alkali in order to effect saponification. After graining, washing, and settling with or without nigre removal, the resulting soap may have a concentration of total fatty acids (as soaps) and unsaponifiables of higher than 80% by weight.

A sufficient amount of water or an aqueous solution may be added to the saponified mass containing the unsaponifiables to form a liquid soap which does not gel to a solidified mass upon cooling to room temperature. Generally, a clear homogeneous liquid results upon addition of the requisite amount of water. Occasionally, certain soap batches when thus treated may have a minor amount of soft, gelatinous masses dispersed in the aqueous solution at room temperature. However, upon the addition of ethyl acetate or other ester solvent, these masses rapidly disintegrate in the surrounding soap solution. More particularly, about 10 to about 20% concentration in the solution of "T. F. A. & U." as hereinafter defined is usually required for successful extraction of saponified still bottoms from fats, particularly animal fats such as tallow. More preferred concentrations productive of particularly efficient results is from about 15 to about 18% "T. F. A. & U."

The requisite dilution of the unsaponifiable concentrate containing the saponified fatty material, e. g. the kettle soap mass, is of material consideration in order to achieve the desired results. At higher concentrations, the soap containing mixture tends to gel or solidify. In addition at such higher concentrations, troublesome emulsions forming at the interface of the solvent and soap solutions in continuous counter-current liquid-liquid extraction, are encountered and may prevent successful and efficient extraction with the ethyl acetate or similar solvent. Other dilute concentrations such as those below about 15%, and more particularly below about 10% are not particularly desirable though extraction can be successfully carried out. Where very dilute concentrations are employed, the mutual solubility of ethyl acetate in water (approximately 8% at 25° C.), the solubility of water in ethyl acetate (approximately 3%), and the considerably greater solubility of ethyl acetate in the soap solution results in increased amounts of solvent in the aqueous phase. Moreover, the time required to extract a given quantity of the unsaponifiables is increased materially, thus decreasing the efficiency and economy of processing desirable for commercial operations.

The soap solution at the desired concentrations has a dark brown color, a pH of about 9.5 and remains essentially liquid at room temperature. In batch type operations, the solution is extracted with ethyl acetate using about one part of

5

solvent to four parts of soap solution by volume, though the solvent ratio is not critical and can vary to the use of an equal volume or several volumes of solvent per volume of solution if desired. It is thus possible to extract considerably over 90% of the total unsaponifiable content, and even over 98%. The crude ethyl acetate or similar solvent extract derived from split tallow bottoms usually contains about 30 to about 40% cholesterol and a percentage of free fatty acids that may total about 25%, and even in certain instances run as high as 30 to 40% fatty acids in the extract. Such free fatty acids result from hydrolysis of the soap solution during solvent extraction. It has been discovered moreover that these fatty acids do not interfere with the recovery of sterols such as cholesterol from the extract. If desired however, the free fatty acids may be removed by washing with a fatty acid neutralizing agent such as sodium carbonate or sodium hydroxide.

This extraction procedure may be utilized in a continuous and counter-current manner with advantage. Basically, such procedure involves the use of a counter-current extraction tower wherein the soap or soap solution is flowed into the upper portion of a vertical extraction tower by any convenient means, such as by gravity or pressure. The solvent comprising ethyl acetate is similarly inserted at a point below the point of introduction of the soap solution. These liquid phases flow counter-currently whereby an extract comprising the unsaponifiables is recovered at the top and the raffinate containing the spent soap solution and a minor amount of solvent is removed from the bottom. The system is preferably operated at normal atmospheric temperature and pressure. However, slightly elevated temperatures approximating the boiling point of ethyl acetate are suitable. A temperature gradient in the tower may be maintained by suitable apparatus in or around the tower and/or a reflux may be used by recycling into the extraction tower a fraction of the extract, to aid in rectification of the rising extract phase.

For a complete and unitary continuous extraction process, it is preferable to attach various units to the extraction apparatus such as a washing tower containing a fatty acid neutralizing agent, a water scrubber to remove any minor amounts of soap in the extract, evaporating and distilling units for the removal of water and recovery of solvent, etc.

The soap solution remaining after the extraction of the unsaponifiables contains a minor proportion of solvent. This solvent can be recovered for example by a variety of methods, including distillation and fractionation. A more satisfactory procedure is to acidify the spent soap, separate the fatty acid layer, which contains about 95% of the total solvent from the extracted soap solution and recover the solvent from this fatty acid layer. The aqueous phase, containing some dissolved solvent, can be neutralized, e. g. with sodium carbonate, and used for diluting succeeding soap masses. The recycling of the spent aqueous phase is advantageous for continuous processing and for maximum recovery as it contains relatively small but significant amounts of sterols.

Selected sterols are recoverable from the wet unsaponifiable solvent extract. Cholesterol (and certain other sterols) forms a molecular complex with oxalic acid when two mols of cholesterol are treated with one mol of oxalic acid. Such

6

addition complexes may be formed and recovered from the solvent extract. The presence of significant amounts of free water in the solvent extract inhibits the formation and separation of the sterol-oxalate complex.

Accordingly, the wet unsaponifiable solvent extract resulting from either batch or continuous extraction such as described above is treated in any suitable manner to substantially remove the water and to form thereby a substantially anhydrous solvent extract. A feature of the use of the ester type solvents utilized herein is the fact that such solvents generally form azeotropes with water, and thereby facilitate the removal of water and the preparation of a substantially anhydrous extract. Thus, the wet unsaponifiable solvent extract can be distilled until a substantially anhydrous extract remains. In this distillation operation the water is removed azeotropically with the solvent generally. Where ethyl acetate is the specific solvent, the ethyl acetate:water azeotrope contains about 8.2% by weight ethyl acetate and boils at 70.4° C., whereas anhydrous ethyl acetate boils at 77.0° C. Illustratively, other ester solvent:water azeotropes are a n-propyl acetate:water azeotrope boiling at 82.4° C., an isopropyl acetate:water azeotrope boiling at 75.0° C., a n-butyl acetate:water azeotrope boiling at 92.0° C., etc.

By removal of the water and control of the amount of solvent present in and distilled from the extract, the unsaponifiable content of the substantially anhydrous solvent extract may be maintained or adjusted to within any desired concentration range. It has been found that an unsaponifiable concentration of approximately 20-40% and more particularly about 20-30% is efficacious in the formation of the oxalate complex.

The solvent extract is then assayed for content of cholesterol (or similar sterol capable of forming the oxalate complex) by the digitonin method and a suitable quantity of substantially anhydrous oxalic acid (0.7 mole for example) per mole of cholesterol or similar sterol is added to the extract, which is then heated under reflux for a short time to effect complete solution of the oxalic acid. The acid ratio is not critical and it is preferred to use a large excess of oxalic acid above the stoichiometric amount of 0.5 mole acid per mole of reactive sterol, of the order of at least about a 40% excess (0.7 mole).

The oxalate complex is relatively insoluble in the solvent extract and tends to precipitate from solution. Preferably the solution may be cooled to induce more complete precipitation of the complex. Upon cooling at room temperature for example, the oxalate complex crystallizes out and is collected on a filter. Aside from what is retained by adsorption of mother liquor on the crystals, all of the dark colored products in the extract pass into the filtrate. After washing with a small quantity of dry ethyl acetate or other suitable solvent such as petroleum ether, the oxalate complex has a light tan or white color. If desired, the oxalate complex may be recrystallized from hot ethyl acetate solution or other suitable solvents which, after an optional treatment with activated carbon to decolorize the solution, deposits pure white crystals upon cooling to room temperature (approximately 25° C.) and below.

The oxalate addition complex may be rapidly decomposed in any suitable manner as by alcohols, acetone, and water to yield the cholesterol

or similar sterol and oxalic acid. A preferred procedure however, is the formation of a solution of the purified complex in ethyl acetate, such as a 15 to 20% solution, to which about 25% of water is added. Upon heating under reflux for about fifteen minutes, separating the water layer and subsequently washing with warm water, substantially all of the oxalic acid may be removed from the mixture. On cooling to about 40° C., the cholesterol (or similar type sterol which had been liberated from the complex) begins to crystallize from the washed acetate. If desired the recovered cholesterol or other sterols may be recrystallized from ethyl acetate or other suitable solvents. The recovery from the oxalate appears to be practically quantitative and pure sterol products may be obtained in this manner. For example, cholesterol of U. S. P. standards may be recovered from the bottoms resulting from the splitting of tallow.

An alternative procedure after saponification of the bottoms and finishing of the soap as previously set forth is the conversion of the saponified mass to a substantially dry condition in any suitable manner, such as drum drying, or spray drying. The moisture content of dried soap mixtures of this character averages a few per cent (about 3 to 5%) in conventional practice. The dried soap may be ground and/or screened to small particles in order to increase the efficiency of subsequent solvent extraction. If desired the soap particles may be in the form or shape of chips, spheres, flakes, granules, etc. The crude solid particles may thereafter be subjected to solid-liquid phase extraction with ethyl acetate or similar type solvent as the sterol solvent by either batch or continuous, including counter-current, operation. The preferred operating procedure however involves the vigorous agitation of the dried soap particles with ethyl acetate at slightly elevated temperatures, and more particularly even at temperatures approximating or at the boiling point of the solvent. The extract may be separated by any means suitable for solid-liquid phase separation, including gravity, filtering, centrifugal force, etc. It has been found that after filtering, and repulping the filter cake if desired, about 90% of the total unsaponifiable content may be recovered in the extract generally.

Saponification procedures for the original unsaponifiable concentrate containing saponifiable fatty material by means of which a substantially anhydrous product is obtained directly may be used advantageously.

Such operations may be batch or continuous and involve generally saponification of a fatty material with alkali during passage through a series of heating coils. An almost anhydrous soap mass is recovered from a flash chamber where water and any other volatile constituents had been vaporized and removed from the saponification mixture. These processes are well known in the art, and may be operated below the decomposition point of the sterols or other unsaponifiables desired to be recovered subsequently.

It is also possible to prepare a substantially anhydrous soap mass and condition the same for solvent extraction during saponification. Such procedure involves the addition of a slight amount of heat to the alkali and saponifiable material and/or the preheating of the reactants

in order to initiate the saponification reaction. Thereafter with agitation the exothermic heat of saponification is utilized to continue the reaction and to vaporize the moisture. Vacuum may be used if desired as the reduced pressure facilitates the flashing off of the water. In the course of the reaction, the soap masses or lumps which are formed are progressively broken up until the soap is in the form of granules. When the saponification step is complete, the substantially dried soap product in powdered form may be recovered and submitted to solvent extraction as previously set forth.

Where concentrated unsaponifiables or sterol residues are obtained with the fatty acid radicals substantially combined as soap, it is not generally necessary to perform the saponification step. Such a suitable concentrate which also constitutes a rich source of sterols is a soap stock obtained from the alkali refining of fats and oils. The alkali refining (either wet or dry) procedure is well known and widely used throughout the art, and as such forms no part of this invention. The foots which result from such treatment with alkalis (e. g. caustic soda, soda ash, and their mixtures), contain a significant portion of the total sterol content present in the original fats and oils. For example, the soap stock from alkali refined soybean may contain as much as 2 or 3% sterols by weight. If suitably dry, the soap stock may be extracted directly with the solvent; or the soap stock may be subjected to a drying operation before extraction where such procedure appears desirable. Alternatively, the soap stock may be diluted to the suitable concentration range so as to avoid formation of a gelled solid and this relatively dilute soap mixture may subsequently be extracted with solvent as previously indicated. The soap stock obtained from the refining of vegetable oils, and particularly soybean oil, are valuable for their content of phytosterols. Vegetable sterols capable of forming an oxalic acid complex such as stigmasterol, may be recovered in high purity and yield by the present invention.

The foots obtained from refining of fatty oils and the like by hydration (e. g. water refining) contain significant amounts of unsaponifiables including sterolic material. Such foots may be added to the soap stock derived from alkali refining of fatty material, and the entire mixture may be processed by any of the aforesaid extraction procedures.

Where the unsaponifiable or sterol concentrates have a significant amount of the total sterols in combined form, such as sterolic esters of fatty acids, sterol glucosides, etc., it is generally desirable to decompose the ester or other type linkage prior to extraction in any suitable manner, as by saponification or hydrolysis, in order to have a maximum free sterol content in the original concentrate and accordingly, a maximum amount of sterols recovered in the solvent extract.

The following are additional specific examples designed to be illustrative of the nature of the invention:

Example 1.—Preparation of kettle soap from splitter second bottoms

A batch of splitter second still bottoms derived from tallow is kettle boiled in a small soap kettle.

Ten pounds of bottoms are boiled with 3.5 lbs of 50° Be', NaOH (10% excess) for three hours. The soap mass is grained with solid sodium chloride, and the clear lye is removed. The soap mass is taken up in water and is boiled again for one hour and grained. The washing, boiling and graining are repeated once more and the final soap settles overnight in a hot room. The following day the separated soap is roll dried. There is recovered 10 lbs. 4 oz. of dry soap.

The analysis of the bottoms used is as follows:

	Per cent
A. V. (KOH)	9.56
S. V. (KOH)	14.96
I. V.	58.50
Unsap.	16.63
Glycerine	0.25
Ash	0.43

Analysis of the finished roll dried soap is as follows:

	Per cent
"T. F. A. & U."	83.90
Unsap. in "T. F. A. & U."	12.20
Free cholesterol in "T. F. A. & U."	6.51
Total cholesterol in "T. F. A. & U."	6.64

Moisture is not determined on this lot of dried soap but from previous experience it would be in the neighborhood of 2.5 to 3.0%. Free alkali would be less than 1% as Na₂O.

The dried soap is screened through a 12 mesh screen before extraction.

Example II.—Extraction from dried soap

Two runs are made as follows indicating the successful extraction of dried soap with ethyl acetate using the soap prepared in Example I:

Run 1.—500 g. of the dried soap is mixed with 1000 ml. of ethyl acetate and the slurry heated and stirred vigorously at 77° C. under reflux for 30 minutes and the extract is removed by hot filtration on a Büchner funnel.

The soap filter cake is repulped similarly three times, heating to 77° C. for 5 minutes with 500 ml. of fresh solvent each time.

By analysis, the soap contains 12.2% unsaponi-

200 ml. of anhydrous ethyl acetate, there is added a solution of 4.6 g. of anhydrous oxalic acid in 75 ml. of ethyl acetate. The solution is refluxed 5 minutes to dissolve the oxalic acid, and left to cool at room temperature whereupon a cholesterol-oxalate complex crystallizes out as a solid phase. The crystallized oxalate is filtered by suction, washed with two 5 ml. portions of anhydrous ethyl acetate and 20.6 g. of oxalic complex is recovered. After distilling off 200 ml. of solvent from the filtrate and washings, an additional 2.2 g. of oxalate complex separates on cooling.

The total amount of oxalate complex (22.8 g.) is dissolved in ethyl acetate to form a 20% solution to which 25% of water is added. The solution is refluxed for 15 minutes and a water layer separated therefrom. The ethyl acetate layer is washed with warm water and the water layer is removed again to remove all of the oxalic acid. On cooling to 40° C., cholesterol is crystallized out from the washed ethyl acetate. The yield of cholesterol is 20.4 g. from the 22.8 of cholesterol-oxalate complex.

Run 2.—This run is made with 500 g. of soap in the same manner as the first one but the soap is only extracted twice, the first time for 30 minutes and the second time for 10 minutes.

	Ethyl Acetate Added, ml.	Volume of Filtrate, ml.	Wt. Material in Extract, g.	Percent Total Unsap. in Extract
1st Ext.	1,500	1,150	43.0	70.6
2nd Ext.	500	470	10.0	16.4
Total	2,000	1,620	53.0	87.0

The oxalate may be prepared from this extract in the manner described above.

Example III.—Extraction from aqueous soap solutions

A 625 g. sample of soap solution (125 g. T. F. A. & U.) containing 16.25 g. of unsaponifiables and 8.12 g. of cholesterol is shaken out with four 1250 ml. portions of ethyl acetate, shaking for three minutes each time.

Each extract is recovered and analyzed and the following results are obtained:

	Wt. of Mat. in Extract, g.	Extract as percent of TFA & U	Percent Fatty Acids in Extract	U. in Ext. as percent TFA & U	Percent Ch. of U in Ext.
1st Ext.	8.42	6.74	9.35	6.11	36.8
2nd Ext.	5.92	4.74	17.20	3.92	45.9
3rd Ext.	4.34	3.49	32.70	2.35	50.2
4th Ext.	4.09	3.27	52.80	1.54	44.8
Total	22.77	18.24		13.92	

A total of 7.4 g. of cholesterol is recovered corresponding to 91.0% of the total present.

Example IV

The soap is prepared from first still bottoms resulting from the splitting of tallow. The analysis of the final soap solution is as follows:

	Per cent
"T. F. A. & U." in soap solution	23.30
Unsap. in soap solution	8.87
Cholesterol in soap solution	0.84

This corresponds to 3.6% cholesterol content in the "T. F. A. & U." which is roughly half the amount usually found in second bottoms.

	Ethyl Acetate Added, ml.	Volume of Filtrate, ml.	Wt. Solids in Extract, g.	Percent Total Unsap. in Extract
1st Ext.	1,000	645	32.0	52.5
2nd Ext.	500	350	10.5	17.2
3rd Ext.	500	445	9.0	14.8
4th Ext.	500	420	3.0	4.9
Total	2,500	1,860	54.5	89.4

Weight of final wet filter cake 693 g.

Weight of final dry filter cake 407 g.

To the 54.5 g. of extracted solids dissolved in

This soap solution on cooling to room temperature gels, but it is found that by diluting to 17.5% "T. F. A. & U." content it can be satisfactorily extracted with ethyl acetate.

Example V.—Continuous extraction

The soap solution is prepared by kettle saponification of second still bottoms resulting from the splitting of tallow. The analysis of the soap solution is as follows:

	Pounds
Soap solution	750.0
"T. F. A. & U."	112.5
Unsap. in "T. F. A. & U."	14.5
Cholesterol in "T. F. A. & U."	7.35

The above soap solution containing 15% by weight "T. F. A. & U." is submitted to continuous extraction with fresh ethyl acetate for 5 1/4 hours at a rate of 500 lbs. of ethyl acetate per hour and the ethyl acetate extract is separated continuously.

The ethyl acetate contains 3.4 pounds of fatty acids, 13.2 pounds of unsaponifiables, and 6.61 pounds of cholesterol in said unsaponifiables. Free water is vaporized as an azeotrope with ethyl acetate and the concentration of unsaponifiables is adjusted until the solution contains 25% unsaponifiables. Anhydrous oxalic acid in an amount 40% in excess of the quantity theoretically required for complete reaction with the cholesterol is added, and the solution is heated under reflux for 10 minutes. Upon cooling and standing at room temperature (25° C.), 4.5 pounds of oxalic complex precipitates as white crystals and is recovered by filtration. Upon decomposition with hot water, there is recovered 4.0 pounds cholesterol having an uncorrected melting point of 146-147° C.

The yield of cholesterol may be increased by further extraction of the spent soap solution with ethyl acetate, and/or by recycling the same to a succeeding batch as previously indicated.

Example VI.—Continuous counter-current extraction

The soap solution is derived from kettle saponification of tallow second bottoms and analyzes as follows:

Soap solution	pounds	672.0
"T. F. A. & U."	per cent	14.9
Unsap. in "T. F. A. & U."	do	12.24
Cholesterol in "T. F. A. & U."	do	5.24

A column 12 feet high, 6 inches in diameter and packed with 1/2 inch Raschig rings is utilized for the continuous counter-current extraction. The soap solution is introduced about 18 inches from the top at a rate of 300 cc. per minute, and wet ethyl acetate (3% water) is introduced 18 inches from the bottom at a rate of 600 cc. per minute. The spent soap solution is drawn off from the bottom of the column continuously, so as to hold the interface about 12 inches from the top of the tower. The soap solution is in the continuous phase, and the ethyl acetate bubbles through as droplets. The extraction is conducted at room temperature and normal atmospheric pressure.

The ethyl acetate extract continuously overflows from the top of the tower into the bottom of a water wash tower which is 10 feet high, 3 inches in diameter and packed with 1/2 inch Raschig rings. The extract is washed continuous-

ly with water pumped into the top of the tower at 60 cc. per minute. The interface is kept at the top of the tower by regulating the withdrawal of the aqueous layer from the bottom. The washed

5 extract overflows into a stripper where the water and most of the ethyl acetate is distilled and their vapors conducted into a condenser. The anhydrous ethyl acetate solution containing about 25% solids is withdrawn from the bottom of the 10 stripper.

The spent soap solution from the bottom of the extraction tower is run continuously into a small tank and mixed therein with some dilute sulfuric acid until a pH of about 5 is obtained.

15 The soap is split thereby into two phases, the upper layer containing fatty acids and ethyl acetate, and the lower layer containing water and ethyl acetate. The layers are separated continuously in a phase separator, the aqueous layer

20 withdrawn from the bottom and the fatty layer overflowing into a steam heated double pipe from which a mixture of ethyl acetate vapors and liquid fatty acids are discharged into a separator. The ethyl acetate vapors are recovered in a condenser and the fatty acids free of ethyl acetate are withdrawn from the separator.

The 672 pounds of soap solution originally contained 5.24 pounds cholesterol. There is 4.89 pounds of cholesterol in the extract and .35 pound

30 in the spent fatty acid layer. This represents a yield of over 93% cholesterol in the extract.

The cholesterol may be recovered from the extract by means of the oxalate complex in the manner described in Examples I and V.

35 In conclusion, it may be noted that the multiple function of ethyl acetate and similar ester solvents in the relationship set forth is most conducive to the performance and attainment of a successful procedure capable of commercial operation.

40 They are quite suitable for the extraction of an unsaponifiable fraction containing sterols from a concentrate, without being good solvents for constituents that may interfere in subsequent processing operations; troublesome emulsions and

45 formation of gels and solids are avoided by their proper use; residual water may be distilled off as an azeotropic mixture with a minor proportion of the solvent with obvious advantages; they are excellent solvents for oxalic acid and relatively 50 poor solvents for the oxalic complex; relatively large yields and pure products are attained by their use even in commercial operation, etc.

Where reference may be made in the description and/or the claims to "fatty material," it is 55 of course intended to include the equivalent fats, fatty oils and waxes, free fatty acids and/or fatty acids chemically combined such as in the form of esters, salts, etc. The term "still bottoms" includes the crude residues containing

60 concentrated unsaponifiables such as a sterol concentrate, and also residual fatty material remaining after the removal by distillation or evaporation of a major portion of vaporizable fatty material. Where reference is made to "anhydrous oxalic acid," it is intended to exclude

65 the complete use of oxalic acid having water in combined form in the molecules, e. g. water of hydration. The phrases "substantially anhydrous solvent extract," "substantially anhydrous

70 ethyl acetate extract," or their equivalent, do not exclude the presence of such minor amounts of water as do not cause material decomposition of, nor prevent extensive formation nor separation of the oxalic complex since excess oxalic acid may act as a dehydrating agent by forma-

tion of a dihydrate. In the symbol "T. F. A. & U." "T. F. A." refers to the total fatty acid content whether in the form of free fatty acids or combined as soap, sterolic esters, etc., and "U" refers similarly to the unsaponifiable content whether sterolic or non-sterolic in nature. All percentages and proportions illustrated are by weight unless otherwise specified.

Since certain changes may be made in carrying out the above process without departing from the scope of the invention, it is intended that all matter contained in the above description shall be interpreted as illustrative and not in a limiting sense.

It is also to be understood that the following claims are intended to cover all the generic and specific features of the invention herein described, and all statements of the scope of the invention, which as a matter of language might be said to fall therebetween.

Having described the invention what is claimed as new and desired to be secured by Letters Patent is:

1. A process of recovering cholesterol from tallow fatty acid still bottoms which comprises saponifying said bottoms to form water soluble soaps of the saponifiable material therein; purifying said saponified bottoms by washing, graining and settling to obtain a settled soap; preparing a dilute aqueous solution of said settled soap; extracting said settled soap solution with ethyl acetate to obtain a wet ethyl acetate solution of sterols; removing at least substantially all the water from said solution by azeotropic distillation; reacting cholesterol in said solution with oxalic acid under substantially anhydrous conditions to form a complex; separating said complex; and decomposing said complex to recover said cholesterol.

2. A process of recovering sterol from fatty acid still bottoms which comprises saponifying said bottoms to form water soluble soaps of the saponifiable material therein and preparing an aqueous soap mixture of the saponified bottoms, extracting said aqueous soap mixture with a liquid ester of a lower fatty acid having at least two carbon atoms and a lower monohydric alcohol to obtain a wet solution of sterol, removing at least substantially all the water from said solution, reacting sterol in said solution with oxalic acid under substantially anhydrous conditions to form a complex, separating said complex, and decomposing the same to recover sterol therefrom.

3. A process of recovering sterol from fatty acid still bottoms which comprises saponifying said bottoms to form water soluble soaps of the saponifiable material therein, preparing a liquid aqueous soap mixture of the saponified bottoms, introducing said liquid aqueous mixture into an extraction zone, introducing as a sterol solvent a liquid ester of acetic acid and a lower monohydric alcohol into said extraction zone below the level of introduction of said aqueous soap mixture, flowing the two liquid phases countercurrently, removing from said zone a wet solution of sterol in said solvent, separately removing from said zone a raffinate phase containing the spent soap, removing at least substantially all the water from said solution, reacting sterol in said solution with oxalic acid under substantially anhydrous conditions to form a complex, separating said complex, and decomposing the same to recover sterol therefrom.

4. A process of recovering sterol from a sterol concentrate having a major proportion of soap in admixture therewith which comprises extracting said concentrate with a liquid sterol solvent, said solvent being an ester of a lower fatty acid and a lower monohydric alcohol, separating a solvent extract having sterol dissolved therein, reacting sterol in said solvent extract with oxalic acid under substantially anhydrous conditions to form a complex of said acid and sterol, separating said complex, and decomposing the same to recover sterol therefrom.

5. A process of recovering selected sterols from still bottoms comprising a major proportion of saponifiable material and having sterols concentrated therein which comprises saponifying still bottoms with an alkaline saponifying agent to form soaps thereof in admixture with said sterols, extracting said saponified bottoms with a liquid sterol solvent, said solvent being an ester of a lower fatty acid having at least two carbon atoms and a lower monohydric alcohol, separating a solvent extract having sterols dissolved therein, reacting selected sterols in said solvent extract with oxalic acid under substantially anhydrous conditions to form a complex of said acid and selected sterols, separating said complex, and decomposing the same to recover the sterols therefrom.

6. A process of recovering sterols by solvent extraction from still bottoms comprising saponifiable material and having sterols concentrated therein which comprises saponifying said bottoms and adjusting the water content thereof to a concentration of up to about 20% total fatty acid and unsaponifiables content by weight whereby a liquid soap mass is obtained which does not gel to a solidified mass in the presence of the solvent, extracting said liquid soap mass with a liquid ester sterol solvent of a lower monohydric alcohol and a lower fatty acid having at least two carbons, separating a solvent extract having sterols dissolved therein, and recovering said sterols.

7. A process of recovering sterol by liquid-liquid phase solvent extraction from a mixture of water and a sterol concentrate having a major proportion of soap and a minor proportion of unsaponifiables which comprises maintaining said mixture as a flowable liquid with sufficient water to prevent the presence of substantial amounts of gelled saponified fatty material in said liquid mixture during extraction, subjecting said liquid mixture to liquid-liquid phase extraction with a liquid lower aliphatic ester sterol solvent having at least two carbon atoms in the acid radical whereby sterol is extracted from said mixture and dissolved in said solvent in the absence of substantial gelled saponified fatty material and without substantial emulsion formation, separating and recovering a solvent extract having sterol dissolved therein.

8. A process of recovering sterol from still bottoms containing the same, which comprises saponifying said bottoms to form water soluble soaps of the saponifiable material therein, forming a dilute aqueous soap mixture of said saponified bottoms, continuously introducing said soap mixture into an extraction zone, continuously introducing as a sterol solvent a liquid ester of acetic acid and a lower monohydric alcohol into said extraction zone below the level of introduction of said soap mixture, flowing the two liquid phases countercurrently, removing from said zone a solvent extract phase with sterol dissolved therein, separately removing from said zone a raffinate

phase containing the spent liquid soap mixture, and recovering said sterol from said solvent extract phase.

ARTHUR IRA GEBHART.
